UNITED STATES PATENT OFFICE.

WILLIAM J. SEMELROTH, OF WESTFIELD, WISCONSIN.

SAW.

Application filed December 19, 1924. Serial No. 756,956.

This invention relates to tools, and the primary object of the invention is to provide a novel combination wood-working tool of the saw type which can be used as a substitute for a number of different tools without any attachment whatever and without any adjustment save a simple one for a very rare use at an odd angle.

Another object of the invention is the provision of a novel tool of the handsaw type having a straight graduated edge to permit the same to be used as a ruler, and a handle provided with angular faces for engaging the work, whereby the straight edge of the blade can be set at different predetermined angles on the work for marking purposes.

A further object of the invention is to provide novel means for pivotally connecting the handle with the saw blade, and novel means for adjustably holding the handle in different angular positions relative to the blade, whereby different angular lines can be drawn on the work when necessary or desirable.

A further object of the invention is to provide a combination square and saw blade having the active edge of the blade provided with different sets of teeth to permit the blade to be used on different kinds of work, that is rip and cross-cut for use at one sawing as fitting sashes or doors.

A still further object of the invention is to provide a novel combination tool of the above character, which will be durable and efficient in use, one that will be simple and easy to manufacture, and one which can be placed upon the market at a small cost.

With these and other objects in view, the invention consists in the novel construction, arrangement, and formation of parts, as will be hereinafter more specifically described, claimed, and illustrated in the accompanying drawings, in which drawings:

Fig. 1 is a side elevation of the improved tool;

Fig. 2 is a longitudinal section through the tool taken on the line 2—2 of Fig. 1 looking in the direction of the arrows;

Fig. 3 is a fragmentary side elevation of the inner end of the saw blade showing the graduated scale carried thereby;

Fig. 4 is a detail perspective view showing the type of screw employed for holding the handle in an adjusted position relative to the blade;

Fig. 5 is a side elevation of a modified type

of the tool showing another form for adjustably connecting the handle of the saw in position;

Fig. 6 is a fragmentary side elevation of a further modified form of the tool, the handle being rigidly connected to the blade; and

Fig. 7 is a fragmentary side elevation showing the opposite side of the tool from Fig. 6.

Referring to the drawings in detail, wherein similar reference characters designate corresponding parts throughout the several views, the letter A generally indicates one type of the improved tool, and B and C denote modified forms thereof.

The improved tool A comprises a handle 10 and a blade 11. The active edge of the blade 11 is provided with a set of relatively large saw teeth 12 and a set of relatively small saw teeth 13. The small saw teeth 13 are arranged adjacent to the inner end of the blade and the different sizes of teeth permit the saw blade to be used on various kinds of work or at one sawing, as fitting sashes or doors. The blade 11 opposite to the active edge thereof is provided with a straight edge 14 which can be provided with a graduated scale 15 in order to permit the blade to be used as a ruler. The outer end of the blade is provided with a straight edge 16 which is disposed at right angles to the straight edge 14.

The inner end of the saw handle 10 is provided with a slot 17 for the reception of the inner end of the saw blade and a suitable hand grip 18 is formed on the handle in rear of said slot. The handle 10 is constructed in a predetermined manner, and associated with the blade 11 in such a way that the tool can be used as a try-square. The upper edge of the handle is preferably formed straight as indicated by the reference character 16 and is normally disposed in longitudinal alignment with the straight edge 14 of the blade. The inner end of the handle is provided with angular faces 17 and 18, and the face 17 is arranged at right angles to the straight edge or face 16 of the handle, while the face 18 is disposed at an angle of substantially 45° to the face 17.

In order to permit the handle 10 to be adjusted relative to the blade 11 the handle is connected with the blade by means of a pivot bolt or the like. Arcuate slots 20 are formed in the blade and these slots are scribed on

a circle which has its axis at the pivot bolt being used as a try-square. If so desired a scale 36 can be marked on one face of the blade and graduated in degrees of a circle in order to facilitate the adjusting of the handle 30 relative to the blade. The opposite longitudinal edges of the handle are provided with straight parallel faces 37 which are disposed at right angles to the inner face 35.

In order to hold the blade and handle in an adjusted position relative to one another, headed screws 21 are provided which extend through the slots 20. The heads of these screws 21 are preferably countersunk within the handle and are adapted to be threaded into nuts 22 countersunk in the opposite face of the handle. It is obvious that by tightening up on the screws 21 the handle can be brought into binding contact with the blade. The blade is also preferably provided with scales 23 graduated into degrees of a circle.

When it is desired to use the tool as an ordinary try-square the handle is disposed in its normal position with the face 17 in alignment with the 90° mark on the blade 20 and the face can then be laid upon the edge of the work with the blade on the face of the work which is to be marked. When it is desired to mark the work at a 45° angle it is merely necessary to place the edge 18 in engagement with the face of the work, as is readily apparent to those skilled in the art. However when other markings are to be made other than a 90° or 45° angle the screws 21 can be loosened and the handle 25 moved to the desired adjusted position, and then locked in place by tightening the screws. It is to be noted at this point that the handle is firmly locked to the blade in two different places on opposite sides of the pivot 19. I also prefer to have the handle 30 provided with right-angularly disposed spirit levels 24 and 25.

The saw blade 11 is provided with several small openings 26 along its length by which, 40 sticking an awl or other point in one hole as a pivot and a pencil or scratch point in another hole, a circle may be scribed, or a segment of a circle, as round the corners of tables or shelves. This is how the saw 45 serves as a compass.

In the modified form B of the improved tool the handle 30 is pivotally connected with the blade 31 by means of a pivot bolt 32 in order to permit swinging movement 50 of the handle relative to the blade. The blade of this form is constructed substantially the same as the blade 11 and is provided with a straight edge 52. The rear end 55 of the blade is provided with an arcuate edge 33 around which the handle is adapted to swing, and the handle is held in its adjusted position by the use of a plurality of relatively small screws 34 which are adapted to impinge against one face of the saw 60 blade. As clearly shown in the drawing the handle is provided with a straight inner face 35 which is disposed normally at right angles to the straight edge 52 of the blade, and the face 35 is adapted to be held in engagement with the work when the tool is 65

In the form C of my invention shown in Figs. 6 and 7 of the drawing the handle 40 is rigidly connected to the blade 41, but the handle and blade are so constructed as to permit the tool to be used as a try-square as will now be described. The upper longitudinal edge of the blade 41 is provided with a straight edge 42 which can of course be graduated similar to the blade 11 and is received in a slot formed in the handle 40. The handle on one side of the blade has its inner edge provided with a straight face 43 which is disposed at right angles to the straight edge 42 of the blade, and thus it is obvious that when the face 43 is placed in engagement with the work that a straight edge 42 will be held at an angle of 90°. The inner edge of the handle on the opposite face of the saw blade is provided with a straight face 44 disposed at an angle of 45° to the straight edge 42 of the blade, and thus it is obvious that when this face 44 is placed in engagement with the work that the straight edge 42 will be disposed at an angle of 45°.

Changes as to details may be made without departing from the spirit or the scope of this invention, but:—

What I claim as new is:—

1. In a combination tool of the saw type, a blade provided with a straight graduated marking edge, a handle pivotally secured to the inner end of the blade and provided with straight angularly disposed work-engaging faces, the blade being provided with arcuate slots, the slots being scribed on a circle having its axis at the pivot point of the handle, adjustable screws carried by the handle and arranged to extend through said slots, nuts countersunk in the handle and arranged to receive said screws, and arcuate scales arranged on the blade adjacent to said slots and graduated into the degrees of a circle.

2. In a combination tool of the saw type, a blade provided with a straight marking edge, a handle pivotally secured to the inner end of the blade and provided with a plurality of work-engaging faces at each side of the blade and at an angle to each other, said blade being provided with arcuate slots scribed on a circle having its axis at the pivot point of the handle, adjustable screws carried by the handle and arranged to extend through said slots, nuts carried by the handle and arranged to receive said

screws, and arcuate scales arranged on the blade adjacent to said slots and graduated into the degrees of a circle.

3. In a combination tool of the saw type, a blade, a handle pivotally secured to the inner end of the blade and provided with a plurality of work-engaging faces at each side of the blade and at an angle to each

other, said blade being provided with an arcuate slot, an adjustable screw carried by the handle and arranged to extend through said slot, and an arcuate scale arranged on the blade adjacent to said slot and graduated into the degrees of a circle. 10

In testimony whereof I affix my signature.

WILLIAM J. SEMELROTH.
